Letters Patent No. 3142 - Dated July 18-1865.

Design for a Medallion of Maj. Gen. Hancock.

The schedule referred to in these Letters Patent and making part of the same.

To all whom it may concern:

Be it known, that I, Franklin Limmons, of the City of Washington, D.C. have originated and produced a new model, of which the accompanying photograph is a true representation.

What I claim as my invention or production, and desire to secure by Letters Patent is The Mezzo-relievo or Medallion Portrait of Maj. Gen. Hancock, represented by the photograph herewith attached.
